(57) CLAIM

The ornamental design for a hula skirt of fabric, as shown and described.

DESCRIPTION

FIG. 1 is a perspective view of the hula skirt of fabric of the invention worn by a user;

FIG. 2 is a side elevation view of the hula skirt of the invention;

FIG. 3 is a top plan view of the invention illustrating the waistband thereof;

FIG. 4 is a plan view of the invention laid in a flat configuration;

FIG. 5 is an enlarged detailed view of the invention taken at section line 5 of FIG. 4;

FIG. 6 is a cross sectional view of a strand of the hula skirt of fabric of the invention taken at section line 6—6 of FIG. 5;

FIG. 7 is a side elevation view of an alternative embodiment of the invention; and,

FIG. 8 is a perspective view of the alternative embodiment of the invention worn by a user.

The broken line showing of a user is for illustrative purposes only and forms no part of the claimed design.

The broken line lines on the waistband shown in FIGS. 1,2,4,5,7 and 8 are understood to represent stitching.
